(57) **ABSTRACT**

A glass atomizer includes a member for e-liquid injection and vapor discharge. The member for e-liquid injection and vapor discharge includes an outer glass tube and an inner glass tube disposed in the outer glass tube. The outer glass tube includes an air inlet. The inner glass tube includes a top end, and the outer edge of the top end includes a plurality of grooves. The top end is integrated with the inner wall of the outer glass tube.

GLASS ATOMIZER

CROSS-REFERENCE TO RELATED APPLICATIONS

Pursuant to 35 U.S.C. § 119 and the Paris Convention Treaty, this application claims foreign priority to Chinese Patent Application No. 202022043745.X filed on Sep. 17, 2020, the contents of which, including any intervening amendments thereto, are incorporated herein by reference. Inquiries from the public to applicants or assignees concerning this document or the related applications should be directed to: Matthias Scholl PC., Attn.: Dr. Matthias Scholl Esq., 245 First Street, 18th Floor, Cambridge, Mass. 02142.

BACKGROUND

The disclosure relates to a glass atomizer.

Conventionally, the atomizers include a cylindrical ceramic core and a spiral heating wire disposed in the cylindrical ceramic core. The spiral heating wire has a low heating power, and thus only a small amount of vapor is produced.

SUMMARY

The disclosure provides a glass atomizer, comprising a member for e-liquid injection and vapor discharge; the member for e-liquid injection and vapor discharge comprises an outer glass tube and an inner glass tube disposed in the outer glass tube; the outer glass tube comprises an air inlet; the inner glass tube comprises a top end; an outer edge of the top end comprises a plurality of grooves; and the top end is integrated with an inner wall of the outer glass tube.

In a class of this embodiment, the member for e-liquid injection and vapor discharge further comprises a seal gasket and a ceramic heating core; the seal gasket comprises a hollow center and is disposed around the ceramic heating core; one end of the ceramic heating core is embedded in a bottom opening of the inner glass tube; a bottom end of the inner glass tube abuts against the seal gasket or the seal gasket is disposed around the bottom end of the inner glass tube.

In a class of this embodiment, the ceramic heating core is in the shape of a concave bowl, and comprises a protruding edge, a bottom, and a heating wire disposed on the bottom.

In a class of this embodiment, the member for e-liquid injection and vapor discharge further comprises a silicone fixed part and a base; the ceramic heating core is disposed on the silicone fixed part; the silicone fixed part is disposed around the base; and a bottom end of the outer glass tube is disposed around the base.

In a class of this embodiment, the base comprises an air hole; the air inlet of the outer glass tube is aligned with and communicates with the air hole of the base.

In a class of this embodiment, the silicone fixed part comprises a recess.

In a class of this embodiment, the member for e-liquid injection and vapor discharge further comprises a seal plug disposed on a top of the inner glass tube and configured to seal a top opening of the inner glass tube after the inner glass tube is filled with e-liquid.

In a class of this embodiment, the member for e-liquid injection and vapor discharge further comprises a joint and an insulation ring; the insulation ring is disposed in a bottom of the base to separate a positive lead from a negative lead of the ceramic heating core and meanwhile fix the negative

2

lead; and the joint is disposed in the insulation ring to fix the positive lead of the ceramic heating core.

In a class of this embodiment, the member for e-liquid injection and vapor discharge further comprises a mouthpiece and a seal ring; the seal ring is disposed around the mouthpiece to seal a gap between the mouthpiece and the outer glass tube thus preventing the leakage of air and vapor; and the mouthpiece is disposed on a top of the outer glass tube.

10 In a class of this embodiment, the outer glass tube and the inner glass tube comprise toughened glass, high temperature resistant poly-cyclohexylenedimethylene terephthalate glycol (PCTG), high temperature resistant resin, high temperature resistant acrylic, an explosion-proof film, or a combination thereof.

15 In a class of this embodiment, the air enters the atomizer via the air inlet of the outer glass tube, flows through the air hole on the base and the recess on the silicone fixed part, drives the vapor produced by the ceramic heating core to pass through a space between the inner glass tube and the outer glass tube, and is discharged from the plurality of grooves of the top end of the inner glass tube for user's inhaling via the mouthpiece.

25 BRIEF DESCRIPTION OF THE DRAWINGS

FIG. 1 is an exploded view of a glass atomizer in accordance with one embodiment of the disclosure;

20 FIG. 2 is a schematic diagram of a glass atomizer in accordance with one embodiment of the disclosure;

25 FIG. 3 is a sectional view of a glass atomizer in accordance with one embodiment of the disclosure;

30 FIG. 4 shows a moving direction of air in a glass atomizer in accordance with one embodiment of the disclosure; and

35 FIG. 5 is an exploded view of an air passage of a glass atomizer in accordance with one embodiment of the disclosure.

DETAILED DESCRIPTION

40 To further illustrate, embodiments detailing a glass atomizer are described below. It should be noted that the following embodiments are intended to describe and not to limit the disclosure.

45 As shown in FIGS. 1-5, the disclosure provides a glass atomizer comprising a mouthpiece 1, a seal ring 2, a seal plug 3, an outer glass tube 4, an inner glass tube 5, a seal gasket 6, a ceramic heating core 7, a silicone fixed part 8, a base 9, a joint 10, and an insulation ring 11. The silicone fixed part 8 comprises a recess 14. The base 9 comprises an air hole 12. The outer glass tube 4 comprises an air inlet 13. The inner glass tube 5 is disposed in the outer glass tube 4. The inner glass tube 5 comprises a top end. The outer edge of the top end comprises a plurality of grooves 15. The top end is integrated with the inner wall of the outer glass tube 4.

50 The seal gasket 6 comprises a hollow center and is disposed around the ceramic heating core 7. One end of the ceramic heating core 7 is embedded in the bottom opening of the inner glass tube 5. The bottom end of the inner glass tube 5 abuts against the seal gasket 6 or the seal gasket 6 is disposed around the bottom end of the inner glass tube 5.

55 The ceramic heating core 7 is disposed on the silicone fixed part 8. The silicone fixed part 8 is disposed in the base 9. The bottom end of the outer glass tube 4 is disposed around the base 9. The insulation ring 11 is disposed in the bottom of the base 9 to separate the positive lead from the negative lead of the ceramic heating core 7 and meanwhile fix the

negative lead. The joint **10** is disposed in the insulation ring **11** to fix the positive lead of the ceramic heating core **7**. The seal plug **3** is disposed on the top of the inner glass tube **5** and is configured to seal the top opening of the inner glass tube **5** after the inner glass tube **5** is filled with e-liquid. The seal ring **2** is disposed around the mouthpiece **1** to seal the gap between the mouthpiece **1** and the outer glass tube **4** thus preventing the leakage of the air and the vapor. The mouthpiece **1** is disposed on the top of the outer glass tube **4**.

When injected into the inner glass tube **5**, the e-liquid penetrates into the surface of the ceramic heating core **7**, and no drops are formed on the surface of the ceramic heating core **7** and no drops leak into between the inner glass tube **5** and the outer glass tube **4**. The air enters the atomizer via the air inlet **13** of the outer glass tube **4**, flows through the air hole **12** on the base **9** and the recess **14** on the silicone fixed part **8**, drives the vapor produced by the ceramic heating core **7** to pass through the space between the inner glass tube **5** and the outer glass tube **4**, and is discharged from the plurality of grooves **15** of the top end of the inner glass tube **5** for user's inhaling via the mouthpiece **1**.

In the disclosure, the grooves **15** and the recess **14** are configured for air ventilation and can present in different forms. For example, the grooves are disposed on the inner edge of the top end of the inner glass tube **5**, or the grooves are replaced by through holes, etc. The grooves **15** of the inner glass tube **5** are not necessarily on the top end of the inner glass tube **5**, but may be on the middle part of the inner glass tube. The top of the inner glass tube **5** and the top of the outer glass tube **4** may be flush, and the mouthpiece **1** is disposed on the top of the outer glass tube **4**. The material of the outer glass tube **4** and the inner glass tube **5** can also be replaced by the same material selected from toughened glass, high temperature resistant poly-cyclohexylenedimethylene terephthalate glycol (PCTG), high temperature resistant resin, high temperature resistant acrylic, an explosion-proof film, or a combination thereof.

The following advantages are associated with the glass atomizer of the disclosure:

1. The glass atomizer comprises an outer glass tube and an inner glass tube, and the vapor produced by the ceramic heating core passes through the space between the inner glass tube **5** and the outer glass tube **4**. This simplifies the member for vapor discharge of the atomizer.
2. The ceramic heating core **7** is in the shape of a concave bowl, and comprises a protruding edge, a bottom, and a heating wire disposed on the bottom, which is novel.
3. The e-liquid is directly injected into the atomizer via the top opening of the inner glass tube, which is easy to operate.
4. The air enters the atomizer via the air inlet of the outer glass tube, flows through the air hole on the base. The design is novel.

It will be obvious to those skilled in the art that changes and modifications may be made, and therefore, the aim in the appended claims is to cover all such changes and modifications.

What is claimed is:

1. A glass atomizer, comprising an outer glass tube and an inner glass tube disposed in the outer glass tube; the outer glass tube comprises an air inlet; the inner glass tube comprises a top end; an outer edge of the top end comprises a plurality of grooves; and the top end is integrated with an inner wall of the outer glass tube.
2. The glass atomizer of claim 1, further comprises a seal gasket and a ceramic heating core; the seal gasket comprises a hollow center and is disposed around the ceramic heating core; one end of the ceramic heating core is embedded in a bottom opening of the inner glass tube; a bottom end of the inner glass tube abuts against the seal gasket or the seal gasket is disposed around the bottom end of the inner glass tube.
3. The glass atomizer of claim 2, wherein the ceramic heating core is in the shape of a concave bowl, and comprises a heating wire.
4. The glass atomizer of claim 3, further comprises a silicone fixed part and a base; the ceramic heating core is disposed on the silicone fixed part; the silicone fixed part is disposed around the base; and a bottom end of the outer glass tube is disposed around the base.
5. The glass atomizer of claim 4, wherein the base comprises an air hole; the air inlet of the outer glass tube is aligned with and communicates with the air hole of the base.
6. The glass atomizer of claim 5, wherein the silicone fixed part comprises a recess.
7. The glass atomizer of claim 6, further comprises a seal plug disposed on a top of the inner glass tube and configured to seal a top opening of the inner glass tube after the inner glass tube is filled with e-liquid.
8. The glass atomizer of claim 7, further comprises a joint and an insulation ring; the insulation ring is disposed in a bottom of the base to separate a positive lead from a negative lead of the ceramic heating core; and the joint is disposed in the insulation ring.
9. The glass atomizer of claim 8, further comprises a mouthpiece and a seal ring; the seal ring is disposed around the mouthpiece to seal a gap between the mouthpiece and the outer glass tube thus preventing the leakage of air and vapor; and the mouthpiece is disposed on a top of the outer glass tube.
10. The glass atomizer of claim 9, wherein the outer glass tube and the inner glass tube comprise toughened glass, high temperature resistant poly-cyclohexylenedimethylene terephthalate glycol (PCTG), high temperature resistant resin, high temperature resistant acrylic, an explosion-proof film, or a combination thereof.
11. The glass atomizer of claim 10, wherein the air enters the atomizer via the air inlet of the outer glass tube, flows through the air hole on the base and the recess on the silicone fixed part, drives the vapor produced by the ceramic heating core to pass through a space between the inner glass tube and the outer glass tube, and is discharged from the plurality of grooves of the top end of the inner glass tube for user's inhaling via the mouthpiece.
